UNITED STATES PATENT OFFICE.

JOHN EHRHARDT, JR., OF ST. LOUIS, MISSOURI.

BUILDING CONSTRUCTION.

Application filed July 23, 1926. Serial No. 124,338.

This invention pertains to building construction and more particularly to the construction of walls and ceilings with wall board.

5 One of the objects of this invention is to provide a construction in which plaster board and other types of wall board may be used and which will provide an improved appearance of the finished wall.

10 Another object is to provide an improved construction for joints and corners in the use of wall board.

Another object is to provide a construction which will be simple and inexpensive 15 to install.

Further objects will appear from the following description taken in connection with the accompanying drawing in which:

Figure 1 is a perspective view partly in 20 section of a portion of a room illustrating the construction of this invention.

Figure 2 is a vertical sectional detail of a building illustrating another application of this invention.

25 Figure 3 is a horizontal section of a building illustrating another application of this invention.

Figure 4 is a detail showing the junction of two partitions.

30 Figure 5 is an enlarged detail of the construction, and

Figure 6 is a perspective view showing another embodiment of this invention.

The ordinary wall board is a building material made up in sheet form of plaster, 35 gypsum, paper or other suitable material and adapted to be applied by simply nailing the same to the studding and then providing a finished wall surface. In the preparation of such wall board, however, it is 40 difficult to provide straight and smooth edges. Accordingly, the meeting points of adjacent slabs usually disclose a more or less rough seam or crack between the edges 45 of adjacent slabs.

In accordance with this invention, the edge of each slab is placed in a recess in the stud or other support so as to hide to a greater or less extent the irregularity of 50 the edge of the slab.

Referring to the drawing, 1 designates a slab or wall board which is mounted upon the studs 2 of the wall or upon the joists 3 of the ceiling. The studs or joists furnish 55 in each case the supports for the wall board.

In accordance with this invention each sup-

port which receives the edge of a slab 1 is provided with a strip or bead 4 upstanding therefrom and extending therealong throughout the length of the slab. This 60 strip or board may be formed on the stud or support by suitably recessing the edge, or it may be formed separately and attached to the support. The latter construction allows for the use of standard studs and 65 joists and permits the application of the strip to the same after they have been put in place in the building.

The strip may be formed with a simple 70 rectangular cross section or it may be formed with one or both sides beveled as illustrated in Figures 2, 3 and 4. The beveled side has the advantage of providing an overhanging edge which may be fitted snugly against the slab so as to overcome to a greater extent 75 the effect of irregularity of the edge of the slab. The strip may be formed on or attached to the support so as to extend along the middle of the edge thereof leaving recesses 5 along the support on each side of 80 the strip. The edges of adjacent slabs or wall boards are fitted into these recesses as illustrated in the drawing and are also secured to the support by nailing or other suitable means. The slab may further be secured to intermediate supports which are not provided with strips 4 as illustrated in Figures 85 1 and 3.

At the corner where wall and ceiling meet, 90 the ceiling slab may be run clear against the wall support, its edge extending into the recess above the edge of the strip 4 as shown in Figure 2. This strip then serves to additionally support the ceiling slab and also to form a clean, sharp corner therewith. 95 The wall slab is then made to abut the lower edge of the strip, which runs horizontally along the top of the wall. This construction may also be used at the vertical corners of the walls as illustrated at A in 100 Figure 3, and also at the meeting points of partition walls as shown in Figure 4.

It will be seen, therefore, that this invention provides a construction which is cheap and simple to install and which provides an improved appearance of the finished walls or ceiling. This improved appearance is due to the placing of the strip 4 between adjacent edges of the slabs 1. The straight edges of the strip 4 tend to hide the rough edges of the slabs so that a clean cut effect is obtained in the finished wall. In many 110

cases such a wall can be finished without the necessity of applying filler or cement in the cracks at the edges of the slabs.

In the embodiment of Figure 6 the strips 5 40 and 41, corresponding to the strip 4 in other views, are formed into moldings, with the recesses 5 formed along their edges. These may be used for picture moldings or for corner moldings between wall and ceiling or between meeting walls. In either case the recess hides the rough edge of the wall board.

While the invention is set forth in the appended claims as applied to a wall, it is understood, of course, that it may be applied as well to a ceiling, the latter being considered as a horizontal wall.

It is obvious that various changes may be made in details of construction without departing from the spirit of this invention; it is, therefore, to be understood that this invention is not to be limited to the details shown and described.

Having thus described the invention, what is claimed is:—

1. In a wall, a supporting member, a beveled strip along said member having a straight overhanging edge, and a sheet of wall board secured to said member with its 30 edge abutting the edge of said strip.

2. In a wall, a supporting member, a doubly beveled strip along said member having straight overhanging edges, and a sheet of wall board secured to said member on each side of said strip with its edge abutting an overhanging edge of said strip. 35

3. In a wall structure, a supporting member, a sheet of wall board extending angularly to said member, a strip having a face with straight edges and extending along said member, one edge of said strip engaging the face of said wall board, and a second sheet of wallboard supported on said supporting member with its edge engaging the other edge of said strip. 40 45

4. In a wall structure, a supporting member, a sheet of wall board extending angularly to said member, and a strip having a face with a straight edge and extending along said member, the face of said strip being at an angle with the face of said wall board and the edge of said strip confining and supporting the edge of said wall board.

5. In a wall structure, a supporting member, a strip along said member having a straight overhanging outer edge spaced from said member, and a sheet of wall board secured to said member with its edge abutting the edge of said strip. 55

JOHN EHRHARDT, JR.
